UNITED STATES PATENT OFFICE.

WILLIAM O. MCKAMEY, OF KNOXVILLE, TENNESSEE.

RAILWAY CAR.

Application filed January 8, 1926. Serial No. 80,062.

My improvement relates particularly to railway cars having hinged bottom doors adapted to be closed for holding a load of material and to be released for discharging the material.

For examples of such cars, I refer to United States Patent, No. 1,268,344, granted to Charles A. Griffith, June 4, 1918, and United States Patent No. 1,268,390, granted to Hugh W. Sanford, June 4, 1918, and United States Patent, No. 1,536,789, granted to Charles A. Griffith, May 5, 1925.

The first two of those patents disclose mine cars having three bottom doors, two of said doors being hinged to the car axles. The last of said patents discloses a mine car having only two bottom doors, both of said doors extending below the axles and not hinged to the axles, the forward door being hinged to a cross shaft at the forward end of the car and the rear door being hinged to a cross shaft which is located between the two car axles. In said car the axles extend across the discharge openings when the doors have been turned downward on their hinges for the discharge of the load in the car. Thus the axles constitute obstructions hindering the discharge of the load. If large lumps of coal form a part of the load, the axles may prevent such load from being discharged.

One of the objects of this invention is to provide for discharge openings substantially as large as the bottom doors. To this end axles extending across the car frame are not used. In lieu of these continuous axles, short or stub axles are applied to the side frame members or side sills of the car in such manner as to allow mounting the car wheels outside of the frame. This arrangement leaves each of the two discharge openings approximately as large as one half of the car bottom.

In the accompanying drawings,

Fig. 1 is a side elevation of a car and a portion of a track illustrating my improvement;

Fig. 2 is a plan of the car shown in Fig. 1;

Fig. 3 is a transverse upright section on the line, 3-3, of Fig. 2, whereby the rear bumper is omitted;

Fig. 4 is a bottom view of the car, portions being broken away;

Fig. 5 is a longitudinal, upright section along the line, 5-5, of Fig. 2;

Fig. 6 is an upright, transverse section on the line, 6-6, of Figs. 1, 5 and 8, looking toward the left;

Fig. 7 is an enlarged upright, transverse section on the line, 7-7, of Fig. 1, looking toward the left;

Fig. 8 is a horizontal section on the line, 8-8, of Fig. 1;

Fig. 9 is an upright, transverse section on the line, 9-9, of Fig. 1, looking toward the right;

Fig. 10 is an upright, middle longitudinal section, showing the car directly after it has discharged its load.

Referring to said drawings: A, A are track rails resting on ties, A¹. B, B are ordinary car wheels applied to the outer ends of short or stub axles, C and C¹. D is the body of the car. D¹ are the side beams or sills forming portions of the car frame, the ends of which beams are joined to and stayed by the bumpers, D². D³, D⁴ are the end walls of the body.

The end of the car at the right, as viewed in the drawings, is the forward end of the car and it is to be understood that the car moves forward for dumping and for closing the doors after the load has been discharged from the car. The discharge is downward between the rails, A, and the place at which the discharge is effected is called the dumping station. Beneath the rails, A, the material discharge from the car may be received by a chute or another car or any other suitable device, not shown.

E is the forward door. This is placed between the side sills and has its forward end hinged to the horizontal hinge rod, E¹, by means of any number of hinge members, E². Said rod has its ends supported by the side sills. Said door extends rearward beneath the line of the forward stub axles, C, and is then extended obliquely rearward and upward and adapted to be engaged and held by the second or rear door as will now be described.

The second or rear door, E³, is placed between the side sills and has its forward end secured by any number of hinge members, E⁵, to the horizontal, transverse, hinge rod, E⁴, having its ends supported by the side sills midway between the ends of the car and between the lines of the stub axles. The body of the door, E³, extends below the line of the axles, C¹, and both ends of said door

are turned obliquely upward between the side sills. The upper faces of the hinge members, E⁵, are concentric to the hinge rod, E⁴. The adjacent end edge of the door, E³, is similarly curved and rests upon and is secured to said hinge members. The rear end of the rear door is normally supported by latch mechanism hereinafter described.

The rear end of the forward door is extended rearward far enough to permit it to rest upon the forward edge of the rear door when the two doors are in the raised or closed position. Each of the doors may be strengthened by having angle members, E⁶, attached to its side edges.

On the rear end of the car and in an upright plane transverse to the length of the car is a large bell crank, F, pivoted at F¹ to the car.

Said bell crank has a downward-directed hook, F², adapted to extend beneath the adjacent bar or arm, F³, on the rear of the rear door the bell crank being so arranged as to bring its pivot, F¹, above its hook, whereby the arm bearing the hook may swing downward and away from the upright, middle, longitudinal plane of the car while the arm, F⁵, of the bell crank extends horizontally outward and by its predominating weight tends to tilt the bell crank so as to move said hook toward said plane. Said hook has a bevel edge, F⁴, adapted to be engaged by the adjacent arm or bar, F³, when the latter is carried upward by the upward movement of the rear part of the door into the closed position.

When said bar, F³, thus rests on the hook, F², said door is held firmly in its upper or closed position, and this condition continues until said hook is moved outward far enough to allow the arm, F³, to descend. Said hook is made to move outward by raising the horizontal arm, F⁵, of the bell crank. To cause said arms to raise automatically, a cam member, A², is placed at one side of the track (the left hand side is shown in the drawing) in position to engage the lower edge of the bell crank arm, F⁵, and cause said arm to move upward on said cam member during the further forward movement of the car, the arm, F⁵, being extended far enough to bring said cam member into the path of the arm. A spring, A⁶, may be applied to the bell crank to aid in holding the crank in normal position in opposition to jolting.

A foundation plate, G, is laid into each of the side sills, D¹, between the flanges of said sills and along the parts of said sills to which the stub axles, C and C¹, and the hinge rod, E⁴, are applied. At each end of said plate, rivets, G¹ extend through the plate and the upright web of the side sill whereby said plate is secured to the sill. Between each end and the middle of the length of said plate, a brace strap, D⁴, is applied

to the body of the car and extended downward over the outer face of the foundation plate. Rivets, G¹, extend through said straps and the foundation plate and the upright web of the side sill, D¹. The plate, 70 G, is preferably a steel casting.

Near each end of the foundation plate, a horizontal bearing, G², is formed integral with said plate and extended inward through the upright web of the side sill. In axial 75 line with the bearing, G², is a pedestal box, G³, also integral with said plate.

A stub axle, C, rests in the bearing, G², and projects inward through the bearing and receives the nut, C². At the outer face 80 of the plate, G, the stub axle has an annular flange, C³, which bears against the outer face of the foundation plate when the nut, C², is drawn against the inner end of the bearing, G². The axle, C, projects outward 85 far enough to enter the hub, B¹, of the wheel, B, the hub of the wheel extending into the pedestal box, G³. A part of said hub within said pedestal box has a circumferential channel, B². A screw, B³, extends through 90 the pedestal box, G³, and into said channel. By this means, the hub is held against endwise movement on the stub axle.

Each end of the hinge rod, E⁴, extends through the upright web of the side sill, D¹, 95 and through the foundation plate, G. At the inner side of the side sill, a nut, E⁷, is threaded around the rod, E⁴. At the outer face of the foundation plate, a nut, E⁸, is threaded around the rod, E⁴. By driving 100 these two nuts against the adjacent faces, said rod will be held firmly for the support of the doors and also for giving stability to the side sills—preventing them from bending sidewise or twisting.

Above each end of the hinge rod, E⁴, a bearing, H, is seated on the upper flange of the adjacent side sill, D¹, and secured thereto by means of rivets and screws. A stay rod, H¹, has its ends resting in the bearings, 110 H. At the inner end of each bearing, said rod has a shoulder, H², adapted to rest against the bearing. Each end of said rod extends through the adjacent bearing. A nut, H³, is threaded around each such end. 115 By driving said nuts inward, they and the shoulders, H², engage the bearings, H. By this means the side sills are given additional stability, the stay rod assisting in holding the side sills against buckling and also 120 against twisting.

When the rear door is in the closed position and held by the latch mechanism, and the rear end of the forward door rests on the forward end of the rear door, as already 125 described, then the car bottom is in position to receive and hold the load of material placed into the car body. When the latch mechanism is released by the cam, A², or manually, at the dumping station, the rear 130

end of that door falls and the forward end turns on the hinge rod, E⁴, whereby the curved forward edge of the rear door is carried rearward from beneath the rear edge 6 of the forward door. Thus the rear edge of the forward door is released, whereupon the rear end of said door falls, the door turning on the forward hinge rod, E¹. Upon the falling of the two doors, the material supported by the doors falls by gravity until the car is emptied.

Now the continued forward movement of the car brings the lower face of the forward door into engagement with a stationary cam member, A³, located upon the track between the rails, A, A, and rising to a sufficient height to force the rear ends of said door upward a little way above its normal or closed position. Said cam member is extended horizontally far enough to maintain its engagement with the forward door until the rear door has in the same manner engaged the inclined portion of said cam and has been forced upward thereby. When the rear door has been thus forced upward, the arm, F³, engages the bevel face, F⁴, of the hook, F², and forces said hook sidewise until said arm is above said hook, whereupon the latter moves sidewise into position beneath 25 said arm. After this has been done, the doors pass successively out of engagement with the cam member, A³. As soon as the forward door is out of such engagement, its rear end falls slightly until its rear edge 30 again rests upon the forward edge of the rear door; and as soon as the rear door passes out of engagement with said cam member, the rear end of said door falls far enough to cause the arm, F³, to descend and 35 rest fully upon the hook, F².

By using the hinge rod, E⁴, at the middle of the car to support the forward end of the rear door and through the latter support the rear end of the forward door, the placing 40 of the axles, C, is not limited relative to the ends of the doors. On the contrary, the two pairs of axles may be so placed as to obtain any desired wheel base.

Furthermore, by using stub axles in lieu 50 of using single axles extending from one side sill to the other, each discharge opening, when the doors are down, is made longer. These larger openings are of real practical importance. In practice, these cars are 55 moved in trains or "trips", the movement across the discharge station being continuous and rapid, in order that all the cars in the train may promptly discharge their loads and move away to make room for another 60 train. In practice, similar cars have been thus operated for the automatic weighing and unloading of as much as fifty tons of coal per minute. This operation, or any operation approaching this in quantity, 65 would be impossible if parts of loads tended

to remain in the cars when the cars are passing the discharge station. For such discharge, the discharge opening must be large enough for easy passing of large blocks of 70 coal. Furthermore, at times the coal of smaller sizes tends to pack and arch whereby downward movement is hindered. Such tendency is reduced by increasing the size of the discharge opening.

It will be observed that the weight of 75 the car body plus the weight of the load is supported by the stub axles and the wheels, and that only the weight of the doors and the material is supported by the hinge shafts, E¹ and E⁴, and the bell crank, F.

By extending the doors as low as shown, the capacity and also the stability of the car are increased. The stability of the car on the track is increased because the load 80 is brought closer to the track rails.

The bottom doors, E and E³, constitute 85 the bottom of the car. It is also to be observed that this car may be operated without releasing the doors. The car may be placed into a rotary dump for sidewise turning, the latch mechanism being held in engagement with the rear door and the forward door, E, being held by the adjacent stub axles against upward movement. The car may also be tilted forward for end dumping. In that case the end wall may, if so desired, be hinged in the well-known manner to permit the ready discharge of the material.

I claim as my invention:

1. In a structure of the kind described, the combination of a car body having side sills, two pairs of stub axles supported by said sills and carrying said body, wheels carrying said axles, a hinge rod between and 100 parallel to the pairs of stub axles, a bottom door hinged by one edge to said rod and extending thence rearward under the rear axles, and mechanism adapted to operate to secure and support the opposite edge of 105 said door when the latter is forced upward into the closed position, substantially as described.

2. In a structure of the kind described, the combination of a car body having side 110 sills, two pairs of stub axles supported by said sills and carrying said body, wheels carrying said axles, a hinge rod located between and parallel to the pairs of stub axles, a door hinged by its forward edge to said 115 rod and extending under the axial line of the rear pair of stub axles and to the rear end of the car, mechanism at the rear end of the car for supporting the rear edge of said door, and a second door hinged to the forward end of the car on a line which is 120 horizontal and transverse to the length of said body and said door extending rearward under the axial line of the forward pair of stub axles and resting on the for- 125 130

ward edge of the rear door when said doors are in the closed position, substantially as described.

3. In a structure of the kind described, the combination of a car body having side sills, two pairs of stub axles supported by said sills and carrying said body, wheels carrying said axles, a hinge rod located between and parallel to the axial lines of the 10 stub axles, hinge members seated on and rising above said rod and having upper faces concentric with the axial line of said rod, a door secured by its forward edge to said hinge members and extending under the 15 axial line of the rear pair of axles and to the rear end of the car, mechanism at the rear end of the car for supporting the rear edge of said door, and a second door hinged to the forward end of the car on a line 20 which is horizontal and transverse to the length of said body and said door extending rearward under the axial line of the forward pair of stub axles and resting on the forward edge of the rear door when 25 said doors are in the closed position, substantially as described.

4. In a structure of the kind described, the combination of a car body having side sills, a pair of stub axles supported by said 30 sills and supporting said body, wheels carrying said axles, a hinge rod supported by the car body, a bottom door coupled by one edge to said hinge rod and extending thence rearward under said stub axles, and mechanism adapted to operate to secure and support the opposite edge of said door when the latter is moved into the closed position, substantially as described.

5. In a structure of the kind described, the combination of a car body having side sills, two pairs of stub axles supported by said sills and supporting said body, wheels carrying said axles, a hinge rod supported by the car body, a bottom door coupled by 45 one edge to said hinge rod and extending thence rearward under a pair of said stub axles, and mechanism adapted to operate to secure and support the opposite edge of said door when the latter is moved into the closed position, substantially as described.

6. In a structure of the kind described, the combination of a car body having side sills, two pairs of stub axles supported by 50 said sills and supporting said body, wheels carrying said axles, door-supporting means supported by the car body, a bottom door

coupled by one edge to said supporting means and extending thence rearward under a pair of said stub axles, and mechanism adapted to operate to secure and support the opposite edge of said door when the latter is moved into the closed position, substantially as described.

7. In a structure of the kind described, the combination of a car body having side 65 sills, a pair of stub axles supported by said sills and supporting said body, wheels carrying said axles, door supporting means supported by the car body, a bottom door coupled by one edge to said supporting 70 means and extending thence rearward under said stub axles, and mechanism adapted to operate to secure and support the opposite edge of said door when the latter is moved into the closed position, substantially as 75 described.

8. In a structure of the kind described, the combination of a car body having side sills, a pair of stub axles supported by said 80 sills and supporting said body, wheels carrying said axles, a transversely hinged bottom extending below the stub axles, and door securing mechanism, substantially as described.

9. In a structure of the kind described, the combination of a car body having side 85 sills, a pair of stub axles supported by said sills and supporting said body, wheels carrying said axles, and a transversely hinged bottom extending below the stub axles, substantially as described.

10. In a structure of the kind described, the combination of a body having side sills, two pairs of stub axles supported by said 95 sills, wheels carrying said axles, a door extending below a pair of the stub axles and transversely hinged to the body, and door securing mechanism, substantially as described.

11. In a structure of the kind described, the combination of a body having side sills, two pairs of stub axles supported by said 100 sills, wheels carrying said axles, a plurality of doors extending below the stub axles and transversely hinged to the body, and door securing mechanism, substantially as described.

In testimony whereof I have signed my name, December 31st, in the year one thousand nine hundred and twenty-five.

WILLIAM O. McKAMEY.
